UNITED STATES PATENT OFFICE

91,964

DESIGN FOR A HOLY WATER FONT

Charles H. Richardson, Atlantic City, N. J.

Application September 2, 1933, Serial No. 49,194

Term of patent 3½ years

To all whom it may concern:

Be it known that I, CHARLES H. RICHARDSON, a citizen of the United States, residing at New York Avenue and Absecon Boulevard, Atlantic City, in the county of Atlantic and State of New Jersey, have invented a new, original, and ornamental Design for a Holy Water Font, of which the following is a specification; reference being had to the accompanying drawing forming a part thereof.

Fig. 1 is a front elevational view of a holy water font showing my new design;

Fig. 2 is a side elevational view thereof; and

Fig. 3 is a front perspective view of the design.

I claim:

The ornamental design for a holy water font as shown.

CHARLES H. RICHARDSON.
